PUMP CASING

Charles I. Longenecker, Wauwataosa, Wis., assignor to Chain Belt Company, Milwaukee, Wis., a corporation of Wisconsin

Application November 19, 1951, Serial No. 17,468

Term of patent 14 years

(Cl. D65—1)

To all whom it may concern:

Be it known that I, Charles I. Longenecker, a citizen of the United States of America, residing at Wauwataosa, county of Milwaukee, State of Wisconsin, have invented a new, original, and ornamental Design for a Pump Casing, of which the following is a specification, reference being had to the accompanying drawing, forming a part thereof.

In the drawing:

Fig. 1 is a perspective view of a pump casing showing my new design, looking toward the left front corner thereof;

Fig. 2 is a front elevational view of the pump casing shown in Fig. 1;

Fig. 3 is a perspective view, taken from the back of the casing, and looking toward the left rear corner thereof; and

Fig. 4 is another perspective view, looking toward the right rear corner thereof.

I claim:

The ornamental design for a pump casing, substantially as shown.

CHARLES I. LONGENECKER.
